SUPPORT STAND FOR A BEER KEG OR THE LIKE

Cecil K. Burns, 11050 Emelita St.,
North Hollywood, Calif. 90028

Filed Apr. 25, 1967, Ser. No. 6,834

Term of patent 14 years

(Cl. D94—3)

FIGURE 1 is a reduced size perspective view of a support stand for a beer keg or the like, showing my new design, the broken line showing of a beer keg being merely for illustrative purposes;

I claim:

The ornamental design for a support stand for a beer keg or the like, substantially as shown and described.
